UNITED STATES PATENT OFFICE.

WERONIKA DOBRON, OF MILWAUKEE, WISCONSIN.

UNDER-SEA-ILLUMINATING MEANS FOR SUBMARINES.

Application filed April 8, 1926. Serial No. 100,720.

This invention relates to certain new and useful improvements in under sea illuminating means for submarines and has for one of its objects to provide a searchlight 5 carried by a side wall of the submarine with a hinged cover for the light opening at the outer side of the wall and with an electrically charged device movable toward the light opening when the cover therefor is 10 raised to prevent sea monsters and the like from charging the light opening.

A further object of the invention is to provide in a submarine structure of the type above set forth, an observation window in 15 proximity of the searchlight with a manually shiftable cover wall therefor.

It is a further object of the invention to provide devices to cause the electrically charged device to move in proximity of the 20 searchlight opening upon elevation of the cover for the light opening in a single operation.

With the above general objects in view and others that will appear as the nature of the 25 invention is better understood, the same consists of the novel form, combination and arrangement of parts hereinafter more fully described, shown in the accompanying drawings and claimed.

30 In the drawings, wherein like reference characters designate corresponding parts throughout the several views,

Figure 1 is a fragmentary side elevational view of a submarine equipped with the under-sea illuminating means showing one of 35 the searchlights in its closed position and the other searchlight open and with an observation window interposed between the searchlights,

Figure 2 is a vertical cross-sectional view 40 taken on line 2-2 of Fig. 1 showing the cable arrangement for operating the cover for the searchlight opening and the electrically charged device,

Figure 3 is a diagrammatic view of the 45 electric wiring for the searchlight and electrically charged device.

Figure 4 is a detail sectional view taken on line 4-4 of Fig. 2,

Figure 5 shows a portion of the submarine 50 walls in section with the electrically charged device illustrated in section and slidable upon guide rods, and

Figure 6 is a fragmentary elevational view 55 of the electrically charged device.

Referring more in detail to the accompany-

ing drawings, the reference numerals 1 and 2 designate the side walls of a submarine and with which wall 2, searchlights are associated with electrically charged devices movable toward the searchlight openings when the latter are in use to prevent sea monsters and the like from charging the searchlight opening and further having observation windows in proximity of the searchlights. 60 65

The illuminating means is in the form of a searchlight comprising a casing 3 containing a lamp having electric cord connection 6 with the socket 7 as shown in Fig. 2, the casing being supported upon the inner face of the 70 side wall 2 of the submarine with a watertight lens 8 set in the opening in the outer end of the casing. A closure door 9 horizontally hinged as at 10 to the outer side of the wall 2 covers the light opening when the 75 light is out of use and is adapted to be elevated to the position shown in Fig. 2.

For the purpose of preventing sea monsters and the like from gathering around the searchlight when the same is in use, the electrically charged device illustrated in Figs. 5 and 6 is adapted to be shifted to a position adjacent the searchlight opening in the submarine wall simultaneously with the opening movement of the closure door 9 and 80 85 such device comprises a pair of metallic plates 11 and 12 spaced by the plate of insulation 13 and secured together in any manner, the rear side of the metallic plate 11 carrying tubular bearings 14 that are 90 95 slideable upon the guide rods 15 carried by the outer face of the submarine wall 2 and spaced therefrom by the insulating collars 16. Prongs 17 anchored to the metallic plate 11 as at 18 pass through openings 19 in the plate 12 and are insulated from the plate 12 by the insulating blocks 20. Similar prongs 21 are anchored as at 22 to the metallic plate 12 and are spaced from the metallic plate 11 by the insulating strip 13, this construction 100 being clearly shown in Fig. 5.

Any number of searchlights may be carried by the side wall of the submarine and arranged in proximity of the searchlight are observation windows, one of which windows 105 is illustrated and designated by the reference numeral 23 with which an overlying hinged cover 24 is associated, the cover being horizontally hinged for vertical swinging movement at the upper edge of the window. The 110 operating means for the hinged window cover 24 is operable from within the sub-

marine body and includes an arcuate arm 25 extending through a water-tight opening in the side wall of the submarine with the outer end thereof pivotally attached as at 26 to one corner edge of the cover and with an operating handle 27 upon its inner end.

The devices for opening and closing the cover wall 9 for the searchlight casing and for raising and lowering the electrically charged device upon the guide rods 15 effects simultaneous operation of these members and such devices include, as shown in Fig. 4 a pair of vertically spaced bracket bearings 28 and 29 that rotatably support cord winding drums 30 and 31 respectively. As shown in Fig. 2, the cord 32 passing over the guide drum 33 that is journaled in the bracket 34 upon the side wall 1 of the submarine has one end thereof passing over guide pulleys 35 and directed through an opening in the side wall 2 for attachment at 36 to the outer side of the free swinging end of the hinged cover 9. The outer end of the cord 32 passes over the drums 31 and 30 in the manner indicated in Figs. 2 and 4 and passing through an opening in the side wall 2 of the submarine body is attached to the inner side of the free swinging end of the cover 9 as at 37. The crank handle 38 associated with the pulley 33 operates the cord 32 to raise and lower the cover 9 for the searchlight casing 3.

The electrically charged device being vertically slidably upon the guide rods 15 is gravitationally lowered and to effect upward sliding movement thereof to a position in proximity of the searchlight opening when the cover wall 9 is elevated, cords attached to the device and associated with the drums 30 and 31 as illustrated in Figs. 2 and 4 are provided. The cords 38 are anchored to the eyes 39 carried by the electrically charged device and passing through the side walls 2 of the submarine body are guided over the drum 30 and also over the drum 31 with the terminal ends thereof anchored to the drum 31. It will, therefore, be seen that when the cord 32 in passing over the drums 30 and 31 for operating the hinged cover 9, causes rotation of the two drums with movement of the cords 38 in opposite directions over said drums for raising the electrically charged device and to permit gravitational lowering movement thereof.

The wiring circuit for the searchlight and the electrically charged devices is diagrammatically illustrated in Fig. 3 and includes the generator —a— having a lead wire —b— communicating with one terminal of the two lamps —c— and branch wires —d— leading to the prongs 17. The other lead wires —e— from the generator having a control switch —f— leads to the other terminals of the lamps —c— and is provided with branches —g— leading to the prongs 21, the lamps

—c— being illuminated while the continuance of the circuit between the prongs 17 and 21 is accomplished when a fish or the like contacts the spaced prongs.

From the above detail description of the invention, it is believed that the construction and operation thereof will at once be apparent, and while there is herein shown and described the preferred embodiment of the present invention, it is nevertheless to be understood that minor changes may be made therein without departing from the spirit and scope of the invention as claimed.

What is claimed is:

1. In under sea illuminating means for submarines, searchlights set into the side wall of the submarine, hinged covers for the outer ends thereof, means for positively moving the covers to open and closed positions, and an electrically charged device movable toward the searchlight opening when the cover therefor is opened.

2. In under sea illuminating means for submarines, searchlights set into the side wall of the submarine, hinged covers for the outer ends thereof, means for positively moving the covers to open and closed positions, an electrically charged device movable toward the searchlight opening when the cover therefor is opened, and operating means for said device associated with the operating means for the cover.

3. In under sea illuminating means for submarines, searchlights set into the side wall of the submarine, hinged covers for the outer ends thereof, means for positively moving the cover to open and closed positions, the operating means for the covers including a manually operable cable, and guide pulleys and drums over which the cable passes with the ends of the cable attached to opposite faces of the free swinging edge of the cover.

4. In under sea illuminating means for submarines, searchlights set into the side wall of the submarine, hinged covers for the outer ends thereof, means for positively moving the covers to open and closed positions, an electrically charged device movable toward the searchlight opening when the cover therefor is opened, the operating means for the covers including a manually operable cable, and guide pulleys and drums over which the cable passes with the ends of the cable attached to opposite faces of the free swinging edge of the cover.

5. In under sea illuminating means for submarines, searchlights set into the side wall of the submarine, hinged covers for the outer ends thereof, means for positively moving the covers to open and closed positions, an electrically charged device movable toward the searchlight opening when the cover therefor is opened, the operating means for the covers including a manually

operable cable, guide pulleys and drums over which the cable passes with the ends of the cable attached to opposite faces of the free swinging edge of the cover, and 5 cables attached to the electrically charged device and associated with the drums to move the device adjacent the light opening when the cover is opened.

6. In under sea illuminating means for 10 submarines, searchlights set into the side wall of the submarine, hinged covers for the outer ends thereof, means for positively moving the covers to open and closed positions, an electrically charged device movable 15 toward the searchlight opening when the cover therefor is opened, the operating means for the covers including a manually operable cable, guide pulleys and drums over which the cable passes with the ends 20 of the cable attached to opposite faces of the free swinging edge of the cover, cables attached to the electrically charged device and associated with the drums to move the device adjacent the light opening when the 25 cover is opened, an observation window adjacent the searchlight, and a manually operable cover therefor.

7. In under sea illuminating means for 30 submarines, searchlights set into the side wall of the submarine, hinged covers for

the outer ends thereof, means for positively moving the covers to open and closed positions, an electrically charged device movable toward the searchlight opening when the cover therefor is opened, and including 35 a pair of metallic plates insulated from each other, a source of electric energy in communication with the plates and adjacently positioned prongs carried by the plates with the prongs on one plate insulated from the 40 prongs on the other plate.

8. In under sea illuminating means for 45 submarines, searchlights set into the side wall of the submarine, hinged covers for the outer ends thereof, means for positively moving the covers to open and closed positions, an electrically charged device movable toward the searchlight opening when the cover therefor is opened, and including 50 a pair of metallic plates insulated from each other, a source of electric energy in communication with the plates, adjacently positioned prongs carried by the plates with the prongs on one plate insulated from the 55 prongs on the other plate, and spaced vertical guide rods on the submarine wall upon which the device is vertically slid able.

In testimony whereof I affix my signature.

Mrs. WERONIKA DOBRON.
